UNITED STATES PATENT OFFICE

169,077

TOOL HOLDING RACK OR SIMILAR ARTICLE

John T. Mains, Jr., Columbus, Ohio, assignor to
The Union Fork and Hoe Company, Columbus,
Ohio, a corporation of Ohio

Application November 10, 1952, Serial No. 22,217

Term of patent 14 years

(Cl. D80—9)

To all whom it may concern:

Be it known that I, John T. Mains, Jr., a citizen of the United States, residing at Columbus, in the county of Franklin and State of Ohio, have invented a new, original, and ornamental Design for a Tool Holding Rack or Similar Article, of which the following is a specification, reference being had to the accompanying drawing, forming a part thereof.

Fig. 1 is a perspective view looking toward the front side of a tool holding rack or similar article, showing my new design;

Fig. 2 is a perspective view looking toward the rear side thereof;

Fig. 3 is a transverse vertical sectional view taken along the line 3—3 of Fig. 1;

Fig. 4 is a bottom plan view.

I claim:

The ornamental design for a tool holding rack or similar article, substantially as shown.

JOHN T. MAINS, JR.
